SPORTING GOODS ARTICLE

Valerie Protzky, New York, N. Y.; The Public Administrator of the County of New York administrator of Valerie Protzky, deceased

Application March 15, 1939, Serial No. 261,894

1 Claim. (Cl. 273—67)

This invention relates to new and useful improvements in goods and articles, used in the line or field of athletics and sports as well as in games, and it has for its main purpose to provide a device of the kind indicated above, which will especially be adaptable for children or boys in their games.

It is another object of this invention to provide a toy device, which when used in plays and games will have a healthy physical effect upon children, while at the same time it will tend to sharpen the intellect and keenness of observation and control of the player's movements during a game.

15 The device, which comprises four cooperating parts, as a unit, may be made of any kind of suitable materials.

Thus the device embodies a head member, two leg or knee members and a hand member, all made to cooperate, as each member is adapted to repel or turn back a ball, when the latter in motion strikes against one of said members.

With the above and other objects in view, this invention consists of the novel features of construction, combination and arrangement of parts, hereinafter fully described, claimed and illustrated in the accompanying drawing forming part of this application, and in which similar characters of reference indicate corresponding parts in all views, and in which:

Figure 1 shows in front elevation a member of the unit attached to the head of a boy; and, also, in a somewhat perspective view a member of the unit attached to the leg of a boy.

35 Figure 2 is a top plan view of the head member.

Figure 3 is a transverse sectional view on the line 3—3 in Figure 2.

Figure 4 is a front elevational view of a member of the unit attached to the hand of the 40 player; while

Figure 5 is a transverse sectional view taken on the line 5—5 in Figure 4; and

Figure 6 is a perspective view of the member secured to the leg of a player, as shown, for instance, in Figure 1.

Referring more particularly to the drawing, 10, 11 and 12, 12 indicate members constituting a unit, or my combined sport or game device.

The member 10 serves a double purpose, first 50 that of shading the eyes of the player; and, secondly, when sufficient dexterity is obtained, that of repelling a ball with the lower surface 14 of said member 10 upon a quick and well calculated movement of the head.

55 The said head member 10, which like the other

members may be made of any suitable materials, consists in detail of a flap 15, which latter in turn comprises an upper and lower layer, 16 and 17, with an in-between stiffening support 18 made, for instance, of cardboard, as shown 5 in Figure 3.

The flap 15 is embedded in a front portion 19 through a slit 20 in the latter, as the endpieces of the layers 16 and 17 are elongated and bent, as shown at 21 and 22, respectively, 10 behind the said front portion 19, the latter being folded upon itself and over said endpieces, as shown in Figure 3.

The stiffening support consists of two layers 18 and 18', which also have their ends bent, as shown at 30 and 30', thus lending stiffness to the front portion 19, while a rear strip 23 forms an inner smooth surface upon the front portion 19, so as to fit the head member 10 snugly to the forehead of a person. Apertures 24 are 20 formed at the ends of the front portion, so that an elastic band 25 may be attached thereto for the purpose of securing the head member 10 to the head of a person.

In Figure 4 has been shown a member 11 25 adapted for attachment to the hand of a player. Said member, which preferably has the shape shown in Figure 4, is secured to the hand by means of straps 26, 26 inserted through holes 27 cut through the surface of the said member. 30

The member 12 shown in Figure 6 is adapted for attachment to the leg above the knee of the player. This member may be made in like manner as the member shown in Figure 2, while straps 28 forming part of the front portion 19' 35 secure said member 12 to the leg.

When a ball 29 is thrown, the player, if the ball is in the proper alignment, will bend his leg so as to hit said ball with the lower surface of the member 12, as may be noted in Figure 1, 40 and has been indicated at 12'.

It is obvious that changes may be made in the form, construction and arrangement of the several parts, as shown, within the scope of the appended claim, without departing from the 45 spirit of the invention, and I do not, therefore, wish to limit myself to the exact construction and arrangement shown and described herein.

What I claim as new, and desire to secure by Letters Patent of the United States, is:

50 In a game and sporting goods article, a head member adapted for attachment to the head of a player and comprising a forwardly extending flap, said flap consisting of an upper and a lower layer of suitable material, sheets of stiffening 55

materials inserted between said layers, a rim portion formed with a central opening therein, and being adapted to receive said layers and stiffening materials, said layers and stiffening materials being bent reversely upon the inner side of the rim portion, and said rim portion having its upper and lower edge portions over-

lapping said layers and stiffening materials, a member covering the inner side of the rim portion, the latter being at each end formed with apertures therein, and straps inserted in said apertures, whereby to secure the head member 5 to the head of a player.

VALERIE PROTZKY.
